UNITED STATES PATENT OFFICE.

WILLIAM R. MICHENER, OF OSWEGO, NEW YORK.

STEAM-GOVERNOR.

SPECIFICATION forming part of Letters Patent No. 242,835, dated June 14, 1881.

Application filed November 29, 1880. (Model.)

To all whom it may concern:

Be it known that I, WILLIAM R. MICHENER, of Oswego, in the county of Oswego, in the State of New York, have invented new and 5 useful Improvements in Steam-Governors, of which the following, taken in connection with the accompanying drawings, is a full, clear, and exact description.

This invention relates to the class of governors which, aside from the ordinary regulating of the ingress of the steam to the cylinder during the operation of the engine, also cut off the flow of steam in case of breakage or disconnection of the governor-belt, and thus 15 prevent the dangers incident to excessive velocity of the engine.

My improvements consist, chiefly, in the combination of a governor-valve case having a single vertical steam-passage with an annular enlargement at its intersection with the lateral induction-passage, and provided, above and below said enlargement, respectively, with a single port, and a valve arranged in the vertical passage, and having at each of the aforesaid 20 ports two peripheral flanges, with a peripheral recess between same, and a steam-passage extended vertically through the axis of said valve, by which construction and combination a governor-valve is obtained which is simple 25 in construction, efficient and sensitive in its operation, and capable of automatically closing the valve in case of accidental slipping or breaking of the governor-belt or defects in the actuating mechanism of the governor.

30 My improvements also consist in improved means of deflecting and uniformly distributing the flow of steam around the valve, all as hereinafter more fully described.

In the accompanying drawings, Figures 1 35 and 2 are vertical sections of a governor, showing my improved valve in various positions; and Figs. 3 and 4 are horizontal sections on lines *x x* and *y y*, respectively.

Similar letters of reference indicate corresponding parts.

45 *G* represents the base of the governor, in the form of a shell or case, having a single vertical steam-passage, *B*, intersected by a lateral steam-induction passage, *A*, said passages being adapted to be connected, respectively, with

the steam-chest and with the steam-pipe in the ordinary manner.

The vertical passage *B* has at its intersection with the passage *A* an annular enlargement, *o*, and is provided above and below this enlargement with single ports *a a'*, through which slides and in which is guided vertically a valve, *V*, which, by means of a rod, *e*, is connected with and actuated by the vibratory governor-arms *D* in the ordinary manner.

55 The valve *V* has at each of the ports *a a'* two external peripheral flanges, *b b' b' b*, which are fitted steam-tight to the peripheral face of said ports. The two flanges at each of the ports are arranged such a distance asunder that the lower flange will close the port when the governor is at rest, and the upper flange will be carried into like position when the governor has attained its maximum speed.

60 A circumferential recess or channel, *c*, in the exterior of the valve between the flanges aforesaid, opens the ports *a a'* as the engine is working at ordinary speed and the valve *V* is held at an intermediate position. Vertical ribs *r* extended across the channels *c* serve to guide 65 the valve in its movement.

70 The valve *V* has extended vertically through its axis a steam-passage, *s*, so that simultaneously with the escape of steam through the lower port, steam is also allowed to pass 75 through the upper port, and thence through the center of the valve, the latter current of steam being thus brought directly in line with the outlet of the passage *B* before uniting the two currents, and at the same time augmenting the capacity of the valve and rendering the 80 same more sensitive in its action.

85 In order to thoroughly distribute the steam completely around the valve *V*, I place in the passage *A* a diaphragm, *u*, sufficiently back of 90 the valve *V* to allow a portion of the steam to circulate between them, said diaphragm deflecting the steam and distributing it completely around the valve and through the ports, as indicated by arrows in the drawings.

95 It will be observed that the steam-space between the deflector *u* and valve *V* communicates directly with and constitutes part of the annular steam-passage *o* surrounding the valve, thus producing the aforesaid effect.

Having described my invention, what I claim as new, and desire to secure by Letters Patent, is—

The improved governor-valve herein described, consisting of the combination of the case G, having a single vertical steam-passage, B, with an annular enlargement, o, at its intersection with the steam-induction passage A, and provided above and below the same with 10 a single port, a a', and the valve V, having at each of said ports two peripheral flanges, b b', and intermediate channels c, and provided with the axial passage s, and the de-

flector u, arranged with a steam-space between it and the valve, said steam-space constituting part of the annular passage o, substantially as shown and set forth.

In testimony whereof I have hereunto signed my name and affixed my seal, in the presence of two attesting witnesses, at Oswego, in the 15 county of Oswego, in the State of New York, this 10th day of November, 1880.

WILLIAM R. MICHENER. [L. S.]
